CLAIM

The ornamental design for a shaped percussion instrument, as shown and described herein.

DESCRIPTION

FIG. 1 is a top, front, left side perspective view of a shaped percussion instrument.

FIG. 2 is a front elevation view of the shaped percussion instrument shown in FIG. 1.

FIG. 3 is a rear elevation view of the shaped percussion instrument shown in FIG. 1.

FIG. 4 is a left side elevation view of the shaped percussion instrument shown in FIG. 1.

FIG. 5 is a right side elevation view of the shaped percussion instrument shown in FIG. 1.

FIG. 6 is a top plan view of the shaped percussion instrument shown in FIG. 1; and,

FIG. 7 is a bottom plan view of the shaped percussion instrument shown in FIG. 1.

Broken lines in the figures indicate environmental structure and/or boundaries and form no part of the claimed design. Portions of the devices not shown in the figures form no part of the claimed design.

1 Claim, 4 Drawing Sheets
